CLAIM

The ornamental design for blender, as shown and described.

DESCRIPTION

FIG. 1 is a front perspective view of a blender showing my new design;

FIG. 2 is a front perspective view thereof, shown with the cover removed for completeness of illustration;

FIG. 3 is a front perspective view thereof, shown with the cover removed and the control panel fully retracted for completeness of illustration;

FIG. 4 is a front view thereof with the control panel partially retracted;

FIG. 5 is a front view thereof with the control panel fully retracted;

FIG. 6 is a right side view thereof with the control panel fully retracted; and,

FIG. 7 is a right side view thereof with the control panel fully extended.

The broken lines are shown for illustrative purposes only and form no part of the claimed design.
